UNITED STATES PATENT OFFICE.

THOMAS P. SPENCER, OF MORRISANIA, NEW YORK.

DESIGN FOR REVOLVING BOTTLE-STANDS.

Specification forming part of Design No. **6,582**, dated April 8, 1873; application filed March 14, 1873.

To all whom it may concern:

Be it known that I, THOMAS P. SPENCER, of Morrisania, in the county of Westchester and State of New York, have invented a Design for a Revolving Stand for Exhibiting Bottles, of which the following is a specification:

The nature of my design is fully represented in the accompanying photographic illustration.

The show-stand consists of a standard-wheel

and racks, made of wire in the form and shape represented in the drawing, so as to present a tasteful and ornamental stand for exhibiting perfumery bottles, &c.

I claim as my invention—

The design for a revolving show-stand, as shown and described.

THOMAS P. SPENCER.
